METHOD OF PRODUCING FREE-FLOWING COMPOSITIONS CONTAINING AN ALKALI METAL MONOPERSULFATE AND THE COMPOSITION PRODUCED THEREBY

Stephen E. Stephanou, Lewiston, N.Y., assignor to E. I. du Pont de Nemours and Company, Wilmington, Del., a corporation of Delaware

No Drawing. Application February 3, 1956
Serial No. 563,191

10 Claims. (Cl. 23—114)

This invention relates to non-caking solid compositions containing the monopersulfates of alkali metal.

Solid oxidizing agents based on monopersulfates have recently become available. The monopersulfates are the salts of monopersulfuric or Caro's acid, H_2SO_5 , in which one of the hydrogen atoms has been replaced. The most common representatives of the group are $NaHSO_5$ and $KHSO_5$. The oxidizing agents are generally prepared by partially neutralizing monopersulfuric acid which contains a relatively high percentage of sulfuric acid. The resulting solids are consequently a mixture of the monopersulfate with the corresponding sulfate and bisulfate.

While these solid compositions are stable and quite effective oxidizing agents, they are somewhat hygroscopic. As they pick up moisture from the air they tend to cake, yielding agglomerates which destroy the free-flowing characteristics of the material. Since the powder is valuable in bleaching and laundering compositions, the necessity for the freedom to run or flow is obvious.

A primary object of the present invention is, consequently, provision of a method of imparting the characteristic or free-flow to compositions containing monopersulfates, the monopersulfates of the alkali metals in particular.

Another object is provision of monopersulfate compositions which are free-flowing in nature.

The above-mentioned and yet other objects are achieved in accordance with this invention by the incorporation in the monopersulfate-containing mixtures of certain alkaline compounds of magnesium and sodium. These compounds may be divided into two groups. The first group comprises alkaline inorganic magnesium compounds, e.g., magnesium oxide and the closely related magnesium hydroxide and magnesium carbonate. The second group comprises alkaline magnesium and sodium salts of mono- and dibasic organic acids, fatty acids in particular. The acids should possess between 5 and 20 carbon atoms. Representative of this second group are magnesium stearate and oleate and sodium adipate, stearate and sebante. Magnesium oxide and the closely related compounds are greatly preferred since they alone of those mentioned are odorless. They are, furthermore, more effective as anti-caking aids.

The quantity of adjuvants needed is not sharply critical and may be referred to as "an effective anti-caking amount." Generally this amount is between about 0.5 and 10% by weight of the weight of the monopersulfate composition to which it is added. Between about 0.5 and 2.0% by weight is usually satisfactory and preferred since larger quantities effect little improvement. Samples

2

containing 0.5% by weight or more of magnesium oxide remain free-flowing when stored under ambient room conditions in vented bottles for six months. Control samples containing no adjuvant cake badly within a few days under the same condition.

The adjuvant may be supplied to the dry monopersulfate composition in any suitable manner. Mixing dry powders of the monopersulfate and the adjuvant followed by tumbling the product in a rotating mixer is quite satisfactory. Mixing the adjuvant with a slurry or solution containing dissolved monopersulfates is less satisfactory because of the possibility of a reaction between the materials.

The anti-caking agent of this invention is effective not only with pure monopersulfates but also with monopersulfates containing inert diluents, i. e. diluents possessing no active oxygen. The corresponding sulfates and bisulfates have already been noted as generally present in the monopersulfate. The mole ratio $KHSO_5:KHSO_4:K_2SO_4$ is generally chosen as about 2:1:1 but other ratios can be employed as shown by copending application S.N. 549,629, filed November 29, 1955. The acid compositions are formed to possess roughly between about 1 and 10% by weight of active oxygen and about 10-90% by weight of the bisulfate.

In addition to the sulfates and bisulfates, alkaline compounds such as the water-soluble members of the group consisting of alkali metal phosphates, silicates, and carbonates are frequently added to counteract the acidity of the monopersulfates in aqueous solution. Sodium or potassium tripolyphosphates, orthophosphates, metaphosphates, pyrophosphates, and other alkaline phosphates, meta- and orthosilicates, and carbonates, bicarbonates and sesquicarbonates are representative of these alkaline diluents but others may also be used. Borax for example may be included in the mixture.

A typical formulation containing about 2% active oxygen by weight may be made up from 42% sodium carbonate, 11% sodium tripolyphosphate, 1% magnesium oxide and 46% of a mixture of $KHSO_5$, $KHSO_4$ and K_2SO_4 carrying initially 5% active oxygen. Generally these alkaline compositions will contain enough sodium or potassium monopersulfate to give an over-all active oxygen percentage of 1-7.5%, i.e. about 10-75% by weight, and a remainder of the diluents mentioned. The alkaline diluents are discussed at length in copending application S.N. 563,177, filed of common date herewith. In the absence of an anti-caking agent, monopersulfate compositions containing these alkaline diluents may cake if the active oxygen content is as low as about 2 or 3%.

The adjuvants of this invention are primarily of value in compositions containing the monopersulfate of an alkali metal. They may, however, be used with other monopersulfates as well. Of the alkali metal salts, those of sodium, potassium and ammonium are the most important. In this specification the term "alkali metals" includes ammonium.

There follow some examples which illustrate the invention in more detail. Percentages given in the examples are weight percentages.

EXAMPLE 1

Separate test samples were made up from sulfate mixtures containing about 5% of active oxygen and possessing initially the $KHSO_5:K_2SO_4:KHSO_4$ mole ratio of

about 1.9:1:1 by adding thereto 10% of a number of adjuvants.

The samples were used to fill identical cylinders made from onion skin paper and sealed at one end to a height of 1 inch. The samples were packed by tapping the cylinders, held within a glass vial, 5 times. The packed cylinders were placed in a desiccator held at a relative humidity of 90% and kept there for 24 hours at 40° C. The cylinders were removed from the desiccator, dried in an oven at 40° C. for 4 hours and then allowed to stand at 10 room temperature for 1 hour at ambient humidity (ca. 20-30%). The samples were rated visually as follows:

Rating 1: The sample poured out of tube easily and showed no bridging or clumping of particles.

Rating 2: The sample poured out of tube but showed 15 bridging and clumping.

Rating 3: The sample caked but the cake could be broken by squeezing the cylinder gently.

Rating 4: The sample produced a firm cake which required more than 100 g. pressure to crush.

Rating 5: The sample formed a solid cake which required over 1000 g. pressure to crush.

Results obtained from samples holding 10% of the adjuvants are shown in Table I.

Table I.—Samples containing 10% of adjuvant

Anti-caking agent:	Rating
Pectin	2
Flour	3
Colloidal silica	3
Gelatin	4
Carboxymethylcellulose	3
Magnesium stearate	2
Sugar	4
Magnesium oxide	1
Tricalcium phosphate	3
Magnesium aluminum silicate (china clay)	3
Calcium silicate	3
Sodium tripolyphosphate	3
Magnesium sulfate	3
Control (no additive)	5

EXAMPLE 2

The procedure of Example 1 was essentially repeated except that only 3% of the anti-caking agent was employed in the samples. Results are shown in Table II.

Table II.—Samples containing 3% of adjuvant

Anti-caking agent:	Rating
Magnesium oxide	1
Magnesium stearate	1
Sodium oleate	3
Sodium adipate+10% SLS	1
Sodium sebacate+10% SLS	1
Stearic acid	3
Starch	3
Control (no additive)	5

SLS is sodium lauryl sulfate, a wetting agent optionally employed.

EXAMPLE 3

The procedure of the Examples 1 and 2 was essentially repeated except that 1% of the anticaking agent was employed. Results are shown in Table III.

Table III.—Samples containing 1% of adjuvant

Anti-caking agent:	Rating
Magnesium silicate	2½
Potassium pyrophosphate	5
Magnesium oxide	1
Tricalcium phosphates	5
Silica gel (colloidal)	5
Magnesium stearate	1
Potassium sulfate	5
Potassium silicate	5
Sodium adipate+10% SLS	1½
Sodium sebacate+10% SLS	1½
Sodium toluene sulfonate	5
Control (no additive)	4

Having described my invention, I claim:

1. The method of imparting free-flowing characteristics to a solid composition containing an alkali metal monopersulfate in an amount equivalent to at least 1% active oxygen, based upon the weight of said composition, comprising incorporating in said composition, in an amount effective to inhibit caking of said composition but not exceeding 10% of the weight of said composition, an anti-caking agent from the group consisting of the oxide, the hydroxide and the carbonate of magnesium and the magnesium and sodium salts of stearic acid, oleic acid, adipic acid and sebacic acid.
2. The method of claim 1 employing 0.5 to 2% of the anti-caking agent.
3. The method of claim 1 wherein the monopersulfate is potassium monopersulfate.
- 20 4. The method of claim 1 wherein the anti-caking agent is magnesium oxide.
- 25 5. The method of claim wherein the monopersulfate is potassium monopersulfate and 0.5 to 2% magnesium oxide is employed as the anti-caking agent.
- 30 6. A free-flowing solid composition containing, based upon the weight of said composition, an alkali metal monopersulfate in an amount equivalent to at least 1% active oxygen and an amount effective to inhibit caking of said composition but not exceeding 10% of an anti-caking agent admixed therewith, said anti-caking agent being from the group consisting of the oxide, the hydroxide and the carbonate of magnesium and the magnesium and sodium salts of stearic acid, oleic acid, adipic acid and sebacic acid.
- 35 7. A composition according to claim 6 which contains 0.5 to 2% of the anti-caking agent.
8. A composition according to claim 6 in which the monopersulfate is potassium monopersulfate.
- 40 9. A composition according to claim 6 in which the anti-caking agent is magnesium oxide.
- 45 10. A composition according to claim 6 in which the monopersulfate is potassium monopersulfate and which contains 0.5 to 2% magnesium oxide as the anti-caking agent.
